UNITED STATES PATENT OFFICE

121,874

DESIGN FOR A GRINDING MACHINE

Milburn A. Hollengreen, Harold E. Balsiger, and
John A. Boller, Waynesboro, Pa., assignors to
Landis Tool Company, Waynesboro, Pa.

Application June 6, 1940, Serial No. 92,866

Term of patent 14 years

To all whom it may concern:

Be it known that we, Milburn A. Hollengreen, Harold E. Balsiger and John A. Boller, citizens of the United States of America, residing at Waynesboro, in the county of Franklin and State of Pennsylvania, have invented a new, original, and ornamental Design for a Grinding Machine, of which the following is a specification, reference being had to the accompanying drawing, forming part thereof.

Figure 1 is a front perspective view of a grinding machine showing our new design; and
Figure 2 is a rear perspective view thereof.

We claim:

The ornamental design for a grinding machine, substantially as shown.

MILBURN A. HOLLENGREEN.
HAROLD E. BALSIGER.
JOHN A. BOLLER.
